UNITED STATES PATENT OFFICE.

LAWRENCE OTTO WITHUN, OF CAPAC, MICHIGAN.

ROTARY DRIER.

1,414,766.

Specification of Letters Patent. Patented May 2, 1922.

Application filed September 24, 1921. Serial No. 502,841.

To all whom it may concern:

Be it known that I, LAWRENCE OTTO WITHUN, citizen of the United States, residing at Capac, in the county of St. Clair and

5 State of Michigan, have invented certain new and useful Improvements in Rotary Driers, of which the following is a specification.

My invention relates to rotary driers and 10 more particularly to driers for grain, but it may equally well be utilized for drying other granular material such as sand, gravel, and the like.

The object of the invention is to provide a 15 machine of this character which produces the desired results in an efficient manner but, at the same time, is of such simple construction that it may be manufactured and erected at very low cost.

20 One embodiment of the invention is illustrated in the accompanying drawings, in which:

Figure 1 shows the drier in perspective view,

25 Figure 2 shows a top plan view of the device,

Figure 3 is a side elevation partly in section and with one wall removed,

30 Figure 4 is a transverse section on line 4—4 of Figure 3,

Figure 5 is a horizontal section of a part of the hopper,

Figure 6 is a fragmentary perspective view of one of the transfer pockets,

35 Figure 7 is a longitudinal section on line 7—7 of Figure 4, of a portion of a drum, and

Figure 8 is a longitudinal section on line 8—8 of Figure 4, of a portion of a drum.

40 The drier consists of an outer wooden stand 15 comprising four uprights or legs 16 held together by longitudinal ties 17 and transverse horizontal ties 18, 19 and 20. At the lower ends of the legs are provided ex-

45 tension legs 21 for raising the drier above the floor when necessary.

Within the stand 15 fits a frame 22 which is preferably built of angle irons. The outside dimensions of this frame are slightly 50 less than the dimensions of the stand so that it may be held inside of the stand and secured thereto by means of bolts. Each cor-

ner of this frame consists of an upright angle 23 and top angles 24 for uniting the former.

55

Between the frame 22 and the stand 15, the spaces are filled by walls 25 which are preferably made of asbestos or any other suitable heat resisting material. These walls extend from the top edge of the frame to the bottom thereof and form a complete cabinet. The longitudinal sides have each a shutter or door 26 which is hinged to the top angles 24 so that it may be swung open outwardly. A small handle 27 is provided 60 at the lower end of the door and a couple of pegs 28 or any other suitable locking means is provided at the lower end thereof to keep the door shut. The purpose of these doors is to give access to the interior of the 65 machine for examination of the different parts or replacement thereof.

The top of the machine is provided with a roof 29, also made of heat resisting material and it has an opening 30 with a sliding 70 shutter 31 to cover this opening.

The drier is open at the bottom and placed over a grating 32 from which hot air is expelled and received within the drier to pass through the same, and the hot air and 80 moisture from the grain will then pass through the opening 30 at the top. Instead of being raised above the floor, as shown in Figure 1, the machine may be let down to receive all of the hot air from the grating 85 32, by removing the extension legs 21, or, a heater may be placed on the floor under the drier for the same purpose.

On top of the drier and near one corner thereof is placed a hopper 35 for receiving 90 the grain or the material to be dried. This hopper is preferably hung upon a column 36 extending upwardly from the stand 15. The hopper, which tapers downwardly, has a rectangular channel 37 extending to near the 95 roof of the drier and a pipe 38 in the bottom of said channel penetrates the end wall of the drier and opens into the top drum 40 to deliver grain thereto. A baffle 39, which is made in the shape of a flat slide of wood 100 or metal and provided with different sized openings 41, is placed transversely in said channel 37. This baffle is intended to regulate the stream of grain entering the drier

and to start the operation, the proper opening 41 is set in the channel 37.

Within the drier are placed a plurality of revoluble drums 40, 42 and 43. The machine shown in the drawings is provided with three drums but the number may be changed as required. All the drums are of the same construction and comprise each a central shaft 44 which is journaled at each end upon the cross ties 18, 19 and 20 respectively. The shafts are given a suitable inclination so that when the drums revolve, the grain will pass from one end to the other of the drums actuated by gravity and the rotation of the drums. As will be noticed in Figure 3, this inclination is alternately to the right and left so that, for instance, as shown in Figure 3, the top and bottom drums 40 and 43 are inclined downwardly 20 toward the right while the drum 42 has the same inclination downwardly toward the left.

Upon each end of the shaft 44 are bolted Z-shaped arms 45 and 46 forming spiders 25 or braces for supporting each end of the drum. These braces are of a different length, as best seen in Figure 3, while the lower drum 43 has one pair of braces 46 extending further into the drum than the braces 45 and this pair of braces are positioned at right angles to each other so that they may be bolted crosswise with regard to the shaft 44 upon the latter. At the upper end of each drum is provided a ring 47 30 which is of angular cross section, one shank of the angle running parallel to the shaft 44 and being bolted or riveted to the braces 45 and 46; the other shank of the ring 47 extending radially to form an inner flange at 40 the upper end of each drum. At the other end of the drums, a plain ring 48 is provided to which the other braces 45 and 46 are bolted or riveted.

Longitudinal ribs 49 are bolted on the outer side of the rings 47 and 48 and intermediary hoops 50 are bolted or riveted to these longitudinal ribs so that the shaft with the braces, rings, ribs and intermediary hoops form a rigid skeleton for the drum. Wire meshing 51 forms the cylindrical wall of each drum and this meshing is preferably reinforced at each end by means of a thin ring 52 of galvanized iron to which the meshing is soldered and bolts 53 hold the rings and meshing together. The wire meshing is secured to the hoops and ribs by means of lashing as indicated at 59.

One end of the shaft 44 for the upper drum 40 has a sprocket wheel or pulley 54 60 connected with a motor for driving the shaft. Another sprocket wheel 55 is also keyed to the same shaft and connected by means of a sprocket chain 56 to another sprocket wheel 57 on the drum next below 65 the top drum. A similar gear 58 is provided

between the middle drum and the lowermost drum but preferably at the other end of the drums.

It will be seen, particularly in Figures 1 and 4, that the drums are staggered in transverse relation to each other, for the purpose of making the machine more compact.

As already described, the tube 38 leading from the hopper opens into the upper end of the upper drum 40 slightly below the axis thereof. The radial flange on the annular ring 47 at this end of the drum is provided to prevent spilling of the grain when entering the drum. The other end, being open, empties the grain that is passed through it into a pocket 60 which conveys the grain by means of a tube 61 into the upper end of the second drum 42, and at the lower end of the second drum is a similar pocket 62 for conveying the grain from the middle drum to the bottom drum, and a third pocket 63 conveys the grain from the lower end of the bottom drum to a bin or other receptacle placed outside the drier.

From the construction of this drier it will be seen that the hot air entering at the bottom thereof will not only surround the drums on all sides but on account of the mesh wiring of the drums the heat will also pass directly through the drums and in this manner while the drums revolve, the grain will be thoroughly dried. The speed of the top drum is preferably greater than that of the lower drums and it has been found that a speed of about twenty-five revolutions per minute is suitable for the top drum while the speed of the lower drums is about twenty revolutions per minute. With this speed it is possible to dry two hundred and fifty bushels in twenty-four hours when the machine, as shown, consists of three drums of about four feet length and ten and a half inches diameter.

Having thus described the invention, what is claimed as new is:

1. In a drum for a rotary drier, a central shaft, a skeleton rigidly secured on said shaft, and a perforated cylinder, having open ends, attached to said skeleton, said skeleton comprising a pair of end rings, a plurality of braces connecting said rings to said shaft, longitudinal ribs secured to said rings, and intermediary hoops secured to said ribs.

2. In a drum for a rotary drier, a central shaft, a skeleton rigidly secured on said shaft, and a perforated cylinder, having open ends, attached to said skeleton, said skeleton comprising a pair of end rings, a plurality of Z-shaped braces connecting said rings to said shaft, longitudinal ribs secured to said rings, and intermediary hoops secured to said ribs.

3. In a drum for a rotary drier, a central shaft, a skeleton rigidly secured on said

shaft, and a perforated cylinder, having open ends, attached to said skeleton, said skeleton comprising a pair of end rings, one of said rings having a flange, a plurality of 55 braces connecting said rings to said shaft, longitudinal ribs secured to said rings, and intermediary hoops secured to said ribs.

4. In a drum for a rotary drier, a central shaft, a skeleton rigidly secured on said 10 shaft, and a cylinder, having open ends, attached to said skeleton, said skeleton comprising a pair of end rings, a plurality of braces connecting said rings to said shaft, longitudinal ribs secured to said rings, and 15 intermediary hoops secured to said ribs, said cylinder having sides of wire mesh and reinforced ends.

5. A rotary drier having a housing with an open bottom and a plurality of inclined 20 revoluble drums mounted therein; said housing comprising a metallic framework, a covering of heat resisting material over and around said framework, and a stand into which said framework and covering fit 25 and to which they are rigidly secured.

6. A rotary drier having a housing with an open bottom and a plurality of inclined revoluble drums mounted therein; said housing comprising a metallic framework, 30 a covering of heat resisting material over and around said framework, and a stand into which said framework and covering fit and to which they are rigidly secured, said framework being provided with extension 35 legs.

7. A rotary drier having a housing with an open bottom and a baffle on top, and a plurality of inclined revoluble drums mounted therein; said housing comprising a metallic 40 framework, a covering of heat resisting material over and around said framework, and a stand into which said framework and covering fit and to which they are rigidly secured.

45 8. A rotary drier having a housing with an open bottom and a plurality of inclined revoluble drums mounted therein; said housing comprising a metallic framework, a covering of heat resisting material over and 50 around said framework, and a stand into which said framework and covering fit and

to which they are rigidly secured, each drum being provided with a central shaft, a skeleton rigidly secured on said shaft, and a perforated cylinder with open ends attached to 55 said skeleton.

9. A rotary drier having a housing with an open bottom and a plurality of inclined revoluble drums mounted therein; said housing comprising a metallic framework, a covering of heat resisting material over and around said framework, and a stand into which said framework and covering fit and to which they are rigidly secured; each drum being provided with a central shaft, a skeleton rigidly secured on said shaft, and a perforated cylinder with open ends attached to 60 said skeleton, the skeleton comprising a pair of end rings, the upper one of said rings having a radial flange, a plurality of Z-shaped braces connecting said rings to said shaft, longitudinal ribs secured to said rings, and intermediary hoops secured to said ribs 65 for supporting said cylinder.

10. A rotary drier having a housing with 75 an open bottom and a plurality of inclined revoluble drums mounted therein; said housing comprising a metallic framework, a covering of heat resisting material over and around said framework, and a stand into 80 which said framework and covering fit and to which they are rigidly secured; each drum being provided with a central shaft, a skeleton rigidly secured on said shaft, a perforated cylinder with open ends attached to 85 said skeleton, the skeleton comprising a pair of end rings, the upper one of said rings having a radial flange, a plurality of Z-shaped braces connecting said rings to said shaft, longitudinal ribs secured to said rings, 90 and intermediary hoops secured to said ribs for supporting said cylinder; a hopper near the top of said frame adapted to deliver the material into the upper end of the top drum, and transfer pockets at the adjacent ends of 95 each pair of drums for conveying the material from an upper to a lower drum and a similar pocket at the lower end of the bottom drum for conveying the material out of the drier.

In testimony whereof I affix my signature.

LAWRENCE OTTO WITHUN. [L.S.]
